UNITED STATES PATENT OFFICE

1,986,733

WIRE COATING APPARATUS

William E. Leonard, Worcester, Mass., assignor to
 The American Steel and Wire Company of New
 Jersey, a corporation of New Jersey

Application September 9, 1931, Serial No. 561,939

1 Claim. (Cl. 91—55)

This invention relates to a process and apparatus for the continuous coating of wire, one of the objects being to produce coated wire entirely free from grease and having a clean, shiny finish.

5 Other objects may later become apparent.

The usual method of coating wire is to draw the same down to within a few thousandths of an inch of the finish size and then to wet draw it to proper size while being coated. Wire that has been coated in this manner is objectionable because it is practically impossible to prevent some of the drawing grease or lubricant from remaining on its surface, which reduces its commercial value.

15 In the drawing:

Figure 1 is a side view showing one form of this invention.

Figure 2 is a top plan view thereof.

Figure 3 is a top perspective view of one of the 20 details of the apparatus shown in Figure 2.

Figure 4 is a top perspective view of a detail of Figure 3.

Having reference to this drawing, the process consists in the use of a reel 2 carrying wire 3, this wire having previously been drawn to finished size so that it is not necessary to further draw it down during the coating operation. This wire is led from the reel 2 and given several turns about a drum 4 positioned in a coating fluid containing tank 5. From the drum 4 it is led through a live rubber wiper 6 carried by an arm 7 which also carries several comparatively fine wires 8 which are wrapped about the wire 3. From here it is passed through a drying and tensioning block 9 to the bottom part of a drum 10, which is driven by a motor 12 so that this wire will be drawn through the various devices which have just been described. The wire goes from the bottom of the drum 10 through a wire straightener 13 of the usual construction and back to the top of the drum 10, a lifting finger member 14 serving to prevent the wire running from the top of the drum 10 down to its bottom. In case the drum 10 is provided with some dividing means carried by itself this finger member 14 will not be necessary.

The drying and tensioning device 9 consists specifically of a frame 15 carrying a pair of blocks 16 having their adjacent side walls constructed to

form a tortuous passage 17. An absorbent cotton strand 18 is positioned in the tortuous passage 17 about the wire 3, and screws 19 are provided for adjustably varying the distance of the separation of the blocks 16. This device serves to tension the wire 3 and at the same time dries it. 5

When the motor 12 is operated the drum 10 draws the wire 3 from the reel 2 and into contact with the coating fluid contained in the tank 5, the wire being given a predetermined number of turns 10 about the drum 4 so that it remains in the coating fluid a sufficient length of time. The rubber wiper 6 removes any surplus coating fluid, and the twisted wires 8 serve to burnish the wire to a brighter finish. The drying and tensioning device 15 9 dries the wire so that when it is wound upon the drum 10 it is ready for commercial marketing. The screws 19 on this device may be adjusted to insure adequate drying. If preferred, some other absorbent material than the cotton strand 18 may 20 be substituted in the passage 17.

Wire coated according to this invention is bright and shiny and, because it is not necessary to draw the wire through dies there is no danger of its being contaminated by grease or other lubricants, 25 such as must necessarily be used to lubricate dies. The apparatus is simple and requires less labor than does the old method of drawing the wire to size during the coating operation.

Although a specific form of this invention has 30 been shown in accordance with the patent statutes, it is not intended to limit the scope of this invention exactly thereto, except as defined in the appended claim.

35 I claim:

In combination, a wire supply reel, a coating fluid containing tank adjacent said reel, a drum arranged in said tank and receiving wire from said reel, a rubber wiper arranged on said tank to work on said wire when leaving said drum, a plurality of fine wires fixed next said rubber wiper and wrapped about the wire leaving the same, a dryer arranged adjacent said fine wires and constructed to include a tortuous absorbently lined passage way through which said wire passes, a receiving 40 drum and a wire straightener, said wire being wrapped about said drum a few times, led to said straightener and returned to the drum for storage. 45

WILLIAM E. LEONARD.
